UNITED STATES PATENT OFFICE.

HUGH J. McDONALD, OF NEW ORLEANS, LOUISIANA.

CLOCK-BANK ARRANGEMENT.

1,251,396.

Specification of Letters Patent. Patented Dec. 25, 1917.

Application filed June 12, 1917. Serial No. 174,276.

To all whom it may concern:

Be it known that I, HUGH J. McDONALD, a citizen of the United States, residing at New Orleans, in the parish of Orleans and

5 State of Louisiana, have invented certain new and useful Improvements in Clock-Bank Arrangements; and I do hereby declare the following to be a full, clear, and exact description of the invention, such as 10 will enable others skilled in the art to which it appertains to make and use the same.

The present invention relates to improvements in clocks in which there is placed a bank for receiving coins that are passed 15 through a coin-controlled mechanism for preventing the operation of the clock winding mechanism except when a proper coin is deposited therein.

The plan proposed to be carried out by 20 my present invention consists in having a banking house issue to its customers the improved clocks with the banks contained therein, and whereof the keys are retained by the banking house, so that after the bank 25 has received the coins used to trip the clock winding mechanism, the customer can at any time remove the bank and deliver it to the banking house, where it will be opened and the amount contained placed to the credit 30 of said customer.

In this way it is the primary object of my present invention to encourage systematic saving of small coins.

Another object of my present invention 35 resides in improving the constructions and operation of devices of the above character as heretofore proposed; one novel purpose being to permit the deposit in the bank of as many coins as desired without requiring 40 the operation of the clock winding mechanism.

It is a further object of the present invention to provide an improved device of the above character in which the bank will be 45 readily removable from the clock structure, and when removed the chute which delivers coins thereto will be automatically closed until the bank is again inserted in place, whereupon the accumulated coins may fall 50 thereinto.

In the accompanying drawings forming a part of this application, and in which similar reference symbols indicate corresponding parts in the several views:

55 Figure 1 is a vertical sectional view through a clock shown provided with a coin-

controlled mechanism constructed in accordance with my present invention and illustrating the parts in one position with the bank in place. 60

Fig. 2 is a similar view with the parts shown in another position and with the bank removed.

Fig. 3 is a vertical sectional view of a clock taken at right angles to Figs. 1 and 2, 65 and illustrating the improved coin-controlled mechanism with the bank in place; and

Fig. 4 is a sectional view of a detail.

Referring more particularly to the drawings, which disclose one embodiment of the present invention, at 1 is designated generally a clock of any suitable construction, there being a spring 2 for driving the clock 75 hands after the usual manner. This spring 75 is coupled in the customary manner to a winding shaft 3, whereon is loosely mounted a pinion 4 and fixedly mounted a ratchet 5. A pawl 6 is pivoted on the pinion 4 and yieldingly pressed into engagement with the 80 teeth of the ratchet 5 by a spring 7.

A gear wheel 8, mounted on a shaft 9, arranged parallel to the winding shaft 3, is in constant mesh with the pinion 4, and is driven thereby when the shaft 3 is rotated 85 in a direction to wind the clock spring 2, which, as shown in Figs. 1 and 2, is the counter-clockwise direction. The pawl 6 permits the winding shaft 3 to be rotated by the spring 2 as it drives the clock arbors in 90 the clockwise direction. The gear wheel 8 carries a rack bar 10 having the notches 11 therein which are designed to be engaged by a tooth on a dog 12; this dog is pivoted in a bracket 13 which is attached to any fixed 95 part, as for instance the upper coin chute 14, as herein shown, into the lower end of which projects the rear end of said dog.

The rack 10 also carries a pin or projection 16 adapted to strike the end of an arm 100 17 carried by a hinged flap 18, which forms one wall of the lower end of the coin chute 14. A spring 19 serves to hold this flap 18 in the closed position shown in Fig. 1.

The lower end of the hinged flap 18 carries a head 20, to which is coupled a rod 21 running to the exterior of the clock casing, where it is provided with a button 22 to be engaged by the fingers for moving the flap 18 when it is desired to allow coins to pass 110 to the bank beneath, without affecting the operation of the coin-controlled apparatus.

To this head 20 is also connected a coin stop 23, which has an end projecting into the upper coin chute 14, as shown clearly from Fig. 2, for the purpose of arresting the passage of coins when the hinged flap 18 is swung outwardly.

Coins are introduced to the upper chute 14 by means of a coin receiver, which includes a hollow barrel 24 having a coin slot 25 and containing a rotary tumbler 26 in which is provided a slot 27 adapted to be brought into registry with the slot 25, as shown in Fig. 3, so that a single coin may be inserted; whereupon the tumbler 26 is revolved to the position shown in Fig. 4, so that the slot 27 may be brought to align with the upper chute 14, thus leaving the coin free to descend in the latter.

Beneath the upper coin chute 14 is a second lower coin chute 28, having a curved upper end 29 slightly offset with respect to the lower open end of the upper chute 14 to prevent the free passage of coins from the one to the other chute. This lower chute 28 delivers through an opening in the top of a casing 30 to a bank or coin receptacle 31, which also has an opening adapted to be brought to register with the bottom of the chute 28, when said bank 31 is properly positioned within the casing 30, as shown in Figs. 1 and 3.

There is a slot 32 in one wall of the chute 28 provided to receive a pivoted finger 33 associated with a spring 34, which is adapted to urge said finger 33 into the chute 28 in the position shown in Fig. 2, where it will arrest the passage of down-coming coins and prevent their passing to the casing 30 or bank 31. This pivoted finger 33 only occupies the position shown in Fig. 2 when the bank 31 is removed. The finger is loosely connected to one end of a lever 35 rocking on a bracket 36 supported from the casing 30 or other part; the opposite end of such lever being joined to the upper end of a vertically reciprocating rod 37 operating in a guide 38.

As shown to advantage in Fig. 2, the lower end of this reciprocating rod 37 is connected to the free ends of a lever 39 having a fulcrum 40 on the framework. This lever 39 extends past a vertically elongated slot 41 formed in the rear wall of the casing 30, and which is provided to receive the beveled nose 42 of a key 43. This key, as shown only in Fig. 3, is fitted through a lock casing 44 situated on the interior of the bank 31, and which is accessible only to the banking house having the key of said bank 31.

In the operation of the apparatus, whenever the clock has run down and needs rewinding, the spring 2 will be prevented from being rewound due to the fact that the dog 12 is in engagement with the notch 11, thus binding the gear wheel 8, pinion 4 and the

winding shaft 3 through the ratchet 5 and pawl 6. It therefore becomes necessary to deposit a proper coin in the apparatus which is placed through the slot 25 in the barrel 24 of the coin receiver at the top of the apparatus. The tumbler 26 is, for this purpose, turned to the position shown in Fig. 3, so that the slot 27 therein may register with the slot 25.

After the coin has been properly deposited and received into the slot 27, the tumbler 26 is revolved to the position shown in Fig. 4 to bring said slot into vertical alignment with the upper coin chute 14. The coin is therefore released and drops by gravity through its upper coin chute 14 until it comes in contact with the hinged flap 18 and the inner end of the dog 12, where it is held as indicated in Fig. 1, the weight of the coin depressing the rear end of the dog 12 and raising its forward end to lift the tooth out of the notch 11. The winding mechanism is therefore released and the turning of the winding shaft 3 in the counter-clockwise direction is no longer prevented.

As this winding shaft 3 is turned by a proper key in a counter-clockwise direction, as looked at from Figs. 1 and 2, the shoulders of the ratchet 5 will engage the free end of the pawl 6 and force the pinion 4 around therewith. As the pinion 4 meshes with the gear wheel 8, this latter wheel will also be rotated but in the opposite direction. The various parts are preferably so related that the winding of the clock spring 2 will only be accomplished after the gear wheel 8 has been turned through one complete revolution to bring the notch 11 again in position to be reengaged by the dog 12, when the same will be released.

As the gear wheel 8 rotates it will carry the pin or projection 16 around therewith, and as the free end of the arm 17 extends in the path of said projection 16, the former will be encountered by the latter when the gear wheel nears the completion of its movement, and such projection 16 will serve to shift the arm 17 from the position shown in Fig. 1 to that shown in Fig. 2, with the result of also swinging the hinged flap 18 outwardly to release the coin and permit it to pass into the opposite upper end 29 of the lower coin chute 28. This coin chute 28 directs the coin through the casing 30 and into the bank 31. When the coin is so released from the position shown in Fig. 1, the dog 12 will be free to return its tooth into the notch 11, and the winding mechanism will again be locked against operation until a subsequent coin is placed therein.

As clearly appears from Fig. 2, when the hinged flap 18 is swung outwardly it carries therewith the stop 23, shifting its end through the wall of the upper chute 14 and bringing it into the coin path. This pre-

vents subsequent coins from passing to the bank except singly at each repeated movement of the flap 18. Moreover, any number of coins may be deposited in the bank 5 31 without disturbing the coin-controlled mechanism by drawing upon the button 22, which, through the rod 21, operates the hinged flap 18.

When the bank 31 is in place within the 10 casing 30, the beveled nose 42 of the key 43, will extend through the vertically elongated slot 41 and encounter the lever 39, raising it to the position shown in Figs. 1 and 3. When this lever 39 is thus elevated 15 it will hold the rod 37 in the upper position shown in Fig. 3, thus tilting the lever 35 and holding the finger 33 without the slot 32 in the wall of the lower chute 28. However, when the bank 31 is removed from the 20 casing 30, the key 43 will, of course, be withdrawn therewith, with the consequence of removing the support from the lever 39; the latter therefore dropping to the position shown in Fig. 2 and carrying there- 25 with the rod 37. This movement will oscillate the lever 35 and will swing the finger 33 through the slot 32 and into the coin path in the lower chute 28. This action will be assisted by the spring 34.

30 It will therefore be seen that if coins are deposited in the apparatus during the interval that the bank is removed, these coins may not be delivered to the casing 30, but will be held by the finger 33 in the lower chute 28 until such time as the bank 31 is returned to its proper position. The accumulated coins will then be permitted to descend to the bank 31. From time to time, as the bank 31 becomes filled with the coins, 35 it is removed from its position in the casing 30 and delivered by the customer to the banking house which has issued the clock to him. At the banking house the bank 31 will be opened and the accumulated coins 40 removed therefrom, and their amount placed to the credit of said customer, after which the bank 31 will be returned for subsequent replacement in the clock.

It will, of course, be understood that the 50 unwinding of the spring 2, to drive the clock members, is not interferred with by the herein-described mechanism, as the spring will unwind and drive the winding shaft 3 in a clockwise direction with respect to the 55 showing of the parts in Figs. 1 and 2; which clockwise rotation of the winding shaft 3 will carry the inclined faces of the ratchet 5 over the free end of the pawl 6, which will readily yield against the influence of the 60 spring 7, whereby no movement will be communicated to the pinion 4 nor gear wheel 8.

It is obvious that those skilled in the art 65 may vary the details of construction and arrangements of parts without departing

from the spirit of my invention, and therefore I do not wish to be limited to such features except as may be required by the claims.

I claim:

1. The combination of a clock, a coin depository in said clock, a winding device for said clock, a coin releasable mechanism for controlling the operation of said winding device, said mechanism including a coin chute communicating with said depository, locking means for said winding device adapted to be tripped by a coin in said chute, means for releasing the coin after the winding device has been rewound, hand- 70 actuated means for operating said last-named means from the exterior of the clock, and a stop connected to move with said coin releasing means to prevent the passage of subsequent coins before said coin releasing 75 means is restored to initial position, substantially as described.

2. The combination of a clock, a winding device for said clock, a coin depository in said clock, a coin releasable mechanism 90 for controlling the operation of said winding device and including a coin chute in connection with said depository, locking means for said winding device adapted to be tripped by a coin in said chute, a movable flap for holding the coin in engagement with said locking means during the rewinding operation, an arm connected to said flap, and a projection movable from said winding device and adapted to engage said arm to shift 100 said flap and release the coin from engagement with said locking means, substantially as described.

3. The combination of a clock, a winding device for said clock, a coin depository for 105 said clock, locking means for said winding device, a coin releasable mechanism for controlling the operation of said winding device and including a coin chute in connection with said depository and adapted to direct a coin 110 against said locking means to release the same, a movable flap for holding the coin in engagement with said locking means during the re-winding operation, hand-actuated means for operating said flap, a stop connected to move with said flap to arrest the passage of subsequent coins before said flap 115 is restored to initial position, and automatic means for shifting said flap to release the coin when the winding operation is completed, substantially as described.

4. The combination of a normally locked device, locking means for preventing the operation of said device including a moving part having a notch therein, a dog having a tooth for engaging said notch to lock the device, a coin-receiving chute arranged in the path of said dog and adapted to direct a coin thereagainst to remove the tooth from said notch, a movable flap forming one wall 125 130

of said coin chute, means normally holding said flap closed to cause the coin to continue in engagement with said dog, an arm on said flap, and means carried by said moving part for engaging said arm to shift said flap for the purpose of releasing the coin, substantially as described.

5. The combination of a normally locked device, locking means for said device, a coin releasable mechanism for unlocking said last-named means and including an upper chute for receiving a coin and directing same against the locking means to release the latter, a second chute having its end adjacent the first-named chute offset to prevent the free passage of the coin thereto, and a normally closed flap forming a wall of the upper chute and adapted to be opened to permit the coin to pass from the upper to
- 10 20 the lower chute, substantially as described.

6. The combination of a normally locked device including a moving part having a notch, a pivoted dog having a tooth normally engaging said notch to lock the device, a chute arranged in the path of said dog for receiving a coin to trip said dog, a second chute having its end adjacent the first-named chute offset with respect thereto to prevent the free passage of the coin, a
- 25 30 coin depository in connection with said second-mentioned chute, a movable flap forming one wall of said first-named chute, means

for normally holding said flap closed and the coin in engagement with said dog, automatic means for shifting said flap to the open position to release the coin from engagement with said dog, and a coin stop movable with said flap and adapted to arrest the passage of subsequent coins when said flap is in the open position, substantially as described.

7. The combination of a clock, a winding device for said clock, a rotating part connected to move with said winding device and having a notch therein, a pivoted dog having a tooth for engaging said notch to lock the winding mechanism, an upper chute in the path of said dog for receiving a coin for tripping said dog, a lower chute having its upper ends offset from said first-named chute, a movable flap forming one wall of said first-named chute for holding the coin in engagement with said dog, means for holding said flap normally closed, an arm on said flap, a projection traveling with said moving part and adapted to engage said arm to move said flap to the open position, a coin stop movable with said flap to prevent the passage of subsequent coins when the flap is open, and hand-actuated means for operating said flap independently of the arm and projection, substantially as described.

In testimony whereof I affix my signature.

HUGH J. McDONALD.
